UNITED STATES PATENT OFFICE.

RALPH L. CONNER, OF WILMINGTON, DELAWARE.

FLOOR PLANER.

Application filed December 21, 1920. Serial No. 432,216.

To all whom it may concern:

Be it known that I, RALPH L. CONNER, a citizen of the United States, residing at Wilmington, in the county of New Castle and State of Delaware, have invented certain new and useful Improvements in Floor Planers, of which the following is a specification.

One object of my invention is to provide an improved floor planer which can be easily pushed and pulled across a floor and which will include a motor driven cutter operative to effectively plane the floor.

Another object is to provide improved means on the planer of my present invention which will sand paper the floor, by power derived from the motor, after the cutter has operated; said means being adjustable to sand paper the overlapping portions which have been cut by the cutter.

A further object is to provide improved means for lifting the cutter out of engagement with the floor at the will of the operator.

These objects, and other advantageous ends which will be described hereinafter, I attain in the following manner, reference being had to the accompanying drawings, in which—

Figure 1 is a side elevation of my improved planer,

Figure 2 is a sectional plan view taken on the line 2—2 of Figure 1,

Figure 3 is a sectional elevation taken on the line 3—3 of Figure 2,

Figure 4 is a sectional plan view taken on the line 4—4 of Figure 3 through the parting of the frame, and

Figure 5 is a fragmentary side elevation showing the sand papered device having been moved to operate upon the floor.

Referring to the drawings, 6 represents a main frame which includes an upper section 7 and a lower section 8, both of which are preferably made of metal. The upper section 7 includes two side rails 9 and 10 which are spaced apart longitudinally as clearly shown in Figure 2. These side rails at their forward ends have depending extensions 11 which have a transversely extending beam 12 connecting them at their bottoms; said beam including two longitudinally extending slots 13. The lower surface of the extensions 11 and beam 12 slant upwardly toward the rear and a gage plate or

shoe 14 is held in engagement with the lower surface of the beam 12 by means of screws or bolts 15 which extend through the slots 13; said screws or bolts having heads of larger width than the widths of the slots 13 so that the shoe can be adjusted forwardly and rearwardly; the bottom surface of the gage plate or shoe 14 being normally horizontal so that the gage plate tapers forwardly as clearly shown in Figures 1 and 3.

The lower section 8 of the main frame is secured to the lower surfaces of the side rails 9 and 10 by screws 16^a so that a parting 16 is formed between the sections 7 and 8. This parting may be machined so as to provide a close and accurate fit and bearings 17 are provided jointly by the upper and lower sections at the line of parting; said bearings serving for the journals of a cutter shaft 18 which has a pulley 19 on one end which is driven by a belt 20 from the pulley 21 of an electric motor 22 which is secured to the top of the upper section 7 by bolts 23. The forward end of the lower section 8 stops short of the extensions 11 and provides an upwardly extending space 24 which leads upwardly to the bottom edges of the side rails 9 and 10 forward of the bearings 17.

A cutter 25 is mounted on the shaft 18 within the frame; said cutter including cutting blades 26 which, when the motor is rotated, will rotate to cut and thereby plane the floor over which the planer may be pushed by a handle 27; said handle at its lower end being secured by the bolts which secure the rear of the motor to the frame. A floor-engaging roller 28 is positioned within the frame and has trunions 29 which have bearings in a bracket 30; said bracket being pivotally mounted forward of the roller on bolts 31. The bracket 30 includes upwardly extending arms 32 between which extends a bar 33. One end 34 of a bell crank lever 35, which is pivoted to the handle 27, is adapted to engage against the bar 33 when the bell crank lever 35 is swung on its pivot and I provide for this purpose, a link 36 which is connected to the other arm 37 of the bell crank lever 35; said link 36 being adjustably connected to the handle 27 and having an adjusting screw 38 which can be moved by the workman so as to force the portion 34 of the bell crank lever 35 in engagement with the bar 33 of the bracket 30, and thereby move the roller 28 down into

engagement with the floor and tilt the entire planer on the gage shoe 14 as a fulcrum and raise or lower the cutter 25 so that its blades will cut any desired depth. This adjusting screw 38 fits a tapped hole 38^a in a member 27^a which is secured to the handle 27 so that by turning the adjusting screw, the link will be moved as above set forth for the purpose of varying the depth of cut of the cutting blades.

It will be understood that the depth of cut may be further regulated by moving the gage plate or shoe 14 forwardly or rearwardly to relatively raise or lower the cutter with respect to the floor. This can be done by loosening the bolts or screws 15 and sliding the shoe 14 either forwardly or rearwardly.

An auxiliary frame 39 has portions pivotally mounted on a rod 40; said rod extending through slots 41 in the main frame 6 adjacent the parting 16; said rod having a bearing in side brackets 42 which have angular ends 43 through which adjusting screws 44 extend; said adjusting screws fitting tapped openings 45 in the rear end of the main frame as clearly shown in Figure 4; tightening screws 46 being provided which extend through lateral slots 47 in the brackets 42 so that after the adjustment has been made by the screws 44, the brackets may be secured in rigid position. The auxiliary frame at its rear end supports a shaft 48 upon which is mounted an abrasive roller such as a sand paper roller 49. The arrangement is such that the sand paper roller 49 can be moved transversely along the shaft 48 and secured in positions overlapping the path cut by the cutter.

To accomplish this purpose, I slidably key the sand paper roller 49 to the shaft 48 by providing a spline 50 in the shaft 48 and supplying a key 51 (see Figure 3) so that the sand paper roller will be rotatably locked to the shaft 48. I lock the sand paper roller in various longitudinal positions on the shaft 48 by means of a latch 52 which is slidably secured to one end of the roller 49 by a screw 53 which extends through a slot 54 in the latch and fits a tapped hole 55 in the end of the roller 49. The latch has a portion 56 adapted to be projected into any of a series of notches 57 in the shaft 48 so that the roller 49 can be secured in any of its adjusted positions at either side of the path cut by the cutter 25, as clearly indicated by the full and dot-and-dash lines in Figure 4.

The auxiliary frame 39 is supported in its raised position by springs 58 which bear on the under part of the auxiliary frame and which have portions which fit within cavities 59 in the lower frame section 8 as clearly shown in Figures 1 and 5. The auxiliary frame 39 has extensions 60 which form a mounting for a bar 61 adapted to be en-

gaged by an arm 62 of a bell crank lever 63; said bell crank lever 63 being pivoted to the handle 27. The arm 64 of the bell crank lever 63 is connected by a link 65 which is slidably mounted adjacent the handle 27 and at its upper end has a loop 66 which can be pulled by the workman to swing the lever 63 and cause the arm 62 to swing the auxiliary frame 39 downwardly against the action of the springs 58 and thereby move the sand paper roller 49 into engagement with the floor. The shaft 48 has a pulley 67 thereon which is driven by a belt 68 from a pulley 69 on the end of the shaft 18 opposite the pulley 19. Thus the shaft 48 and sand paper roller 49 are driven from the motor through the medium of the shaft 18.

In operation the planer can be moved across the floor for the cutting action and during this action the planer rests on the shoe 14 and roller 28; the gage of cut being regulated by the adjusting screw 38 or the shoe 14. If it is necessary during this action or during the rearward movement of the planer to disengage the cutter from the floor, the same can be done by the workman merely lifting slightly on the handle 27 and rocking the planer on the gage shoe 14 as a fulcrum and I preferably provide the shoe 14 with a forward smooth rounded edge 14^a to permit this action without injuring the floor, or the workman to disengage the cutter from the floor can rock the planer in an opposite direction and in order to provide against any possibility of injuring the floor if this latter movement is resorted to, I round the rear corners 8^a of the lower frame section 8 as clearly shown in Figure 1. When using the sand papering device the cutter can be first moved into an inoperative position relatively to the floor by operating the adjusting screw 38 and then the workman can move the link 35 to swing the sand paper roller 49 down into engagement with the floor as above specified.

It will be noted that if the belt 68 becomes slack by use that this slack can be taken up by loosening the bolts 46 and turning the adjusting screws 44. In this manner the auxiliary frame 39 can be moved rearwardly to take up for the slack of the belt 68 after which the screws 46 can be again tightened and hold the parts in their adjusted positions.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A planer of the character described including a cutter having knives for initially planing a floor; an abrasive device optionally movable into engagement with the floor; and adjustable means for transversely moving said abrasive device in a plane approximately parallel with the floor and relatively to the cutter whereby the abrasive device can overlap to various extents the portion of the floor planed by the cutter; substantially as described.
2. A planer of the character described including a main frame; a drive shaft rotatably mounted in said main frame; brackets connected to said main frame and adjustable toward and from said main shaft; an auxiliary frame pivotally supported on said brackets; a surface removing device supported on said auxiliary frame; means for moving said auxiliary frame in either direction on its pivotal support; and means

for rotatably connecting said shaft with 25 the surface removing device whereby the latter will be actuated; substantially as described.

3. A planer of the character described including a main frame; a cutter rotatably mounted therein; means carried by said frame for rotating said cutter, whereby the latter will plane a floor when the frame is moved over the floor; a rotatable shaft carried by said frame; an abrasive roller 30 35 slidably keyed to said latter shaft whereby it can be moved in the direction of the width of the path cut by said cutter; and means for locking said abrasive roller to its shaft in various adjusted positions; substantially as described.

In testimony whereof I have signed my name to this specification in the presence of two subscribing witnesses.

RALPH L. CONNER.
